CLAIM

The ornamental design for a display screen or portion thereof with graphical user interface, as shown and described.

DESCRIPTION

The FIGURE is a front view of a display screen portion thereof with graphical user interface showing the claimed design.

The broken lines of uneven length in the FIGURE show the display screen and form no part of the claimed design. The broken lines of even length in the FIGURE show graphical

(Continued)

elements of a graphical user interface and form no part of the claimed design. Stippling shown in the FIGURE illustrates a contrast in appearance.
